UNITED STATES PATENT OFFICE.

WILLIS R. MARKLEY, OF FINDLAY, OHIO.

INSULATOR.

1,021,059.

Specification of Letters Patent. Patented Mar. 26, 1912.

Application filed January 4, 1911. Serial No. 600,767.

To all whom it may concern:

Be it known that I, WILLIS R. MARKLEY, a citizen of the United States, residing at Findlay, in the county of Hancock and 5 State of Ohio, have invented a new and useful Insulator, of which the following is a specification.

It is the object of the present invention to provide an improved insulator for electrical 10 conductors and more particularly in that of such insulators which are formed of porcelain or other similar insulating material and in two sections between which the wires of other electrical conductors are clamped by 15 a screw or bolt serving also as a means for securing the sections in assembled relation to a support. Insulators of this type are usually formed with flat ends which are designed to be disposed against the support to 20 which the insulator is attached and unless the support is plane upon its face against which the insulator is disposed, the insulator is liable to not set firmly against the support and in time will either work loose or will 25 become broken by the constant strain exerted upon it.

One aim of the present invention is to therefore construct the insulator at its ends 30 of such form that the ends will seat firmly against an uneven support as well as an even or plane one.

As before stated insulators of this type are formed of sections secured together by the same screw or bolt which secures them 35 in assembled relation to the support and consequently, the sections are formed with aligned registering openings through which the said securing bolt or screw is fast. Furthermore, the faces of the insulator sections which are disposed together in assembling the sections, are inclined to the axis of 40 the device, and a further aim of the invention is to reinforce the edges of the openings in the sections at these faces by the formation upon the sections of bosses and seats 45 oppositely located so that when the sections are assembled, the boss of one section will rest in the seat in the other section.

In the accompanying drawings, Figure 1 50 is a view in side elevation of the insulator embodying the present invention. Fig. 2 is a vertical transverse sectional view therethrough. Fig. 3 is a horizontal sectional view on the line 3—3 of Fig. 2. Fig. 4 is a 55 plan view of one of the sections of the insulator.

As heretofore stated, the insulator embodying the present invention consists of two sections and as these sections are counterpart in construction and form, a description of one will suffice for both. Each section is substantially undulate in form and is indicated by the numeral 5. For a purpose to be presently explained, the base of each member is formed with an annular 60 depending shallow flange 6 molded integral with the body of the section. Also, each section is formed axially with a bore 7 and at that end which opens through the base of the section, the respective bore 7 is widened 70 to receive the head of a securing screw or bolt 8 designed to be engaged through the bores 7 of the two sections when they are properly fitted together and to be screwed into a support 9 which may be a board, 75 strip or in fact any other wooden element.

The inclined face of the sections is, at its end remote from the base of the undulate section, flattened as at 9' and at its opposite end is flattened as at 10. Between these flattened portions, the inclined face of the section is substantially plane. Each flattened portion of the said face of the section is formed with a transversely extending substantially V-shaped groove, the walls of 85 which are serrated or roughened as is clearly shown in Fig. 4 of the drawings. It will at this point be readily understood that in assembling the sections, the same are disposed with their inclined faces abutting and the 90 flattened portion 9' of the said face of one section resting against the portion 10 of the corresponding face of the other section, in the manner illustrated in Figs. 1 and 2 of the drawings. Near the portion 9' of its inclined face, each of the sections 9 is formed with a seat or recess 12 the bottom wall of which is substantially crescent shape in top plan and from the said inclined face at a corresponding point near the portion 10 95 thereof, there is formed a lug 13 which is substantially crescent shaped in cross section and is designed to fit snugly in the seat 12 in the other section 5 when the two sections are 100 properly assembled. It will be noted that the lug 22 partly surrounds the end of the bore 7 which opens through the inclined face of the section so that the edges of the wall of this bore at its end are materially strengthened and are not liable to be chipped. It 110 will also be understood that by forming the seats or recesses 12 with substantially cres-

cent shaped bottom walls and forming the lug with seats in the recesses, crescent shaped in cross section, the diameter of the body is not materially increased although 5 exceptionally well reinforced.

From the foregoing description of the invention it will be readily understood that the edge of the wall of the bore 7 in each section, at that end which opens through the 10 said inclined face of the section, is materially reinforced by forming the said face with the recesses or seats 12 and the lugs 13, the lug and recess of each section being relatively offset through opposite sides of the 15 axis of the bore. By thus reinforcing the edge of the wall of the bore of each section, chipping of this edge is prevented and consequently this section will more perfectly fit together. It will be further understood 20 that the faces of the section, or in other words the ends of the insulator as a whole, being formed with the shallow flanges 6, more readily adapt themselves to an uneven support or surface to which the device is 25 attached than they would if formed flat as is usually the case. It will be further understood that the engagement of the lugs 13 in the recesses 12 serves also to prevent the

conductor becoming in any way engaged by the securing screw or bolt which holds the 30 sections of the insulator together.

What is claimed is:

An insulator of the type described, including complementary members, each having an inclined face and diagonally opposite 35 flat horizontal surfaces at the upper and lower terminals of said inclined face, respectively, said flat surfaces having therein transverse substantially V-shaped grooves, with roughened walls, said inclined faces 40 also having at diagonally opposite points crescent-shaped recesses and also correspondingly shaped bosses, said complementary members having aligned bore-forming 45 openings therethrough, and securing means insertable through said bore, said crescent-shaped bosses and recesses being relatively offset through to the opposite sides of the axis of said bore.

In testimony that I claim the foregoing as 50 my own, I have hereto affixed my signature in the presence of two witnesses.

WILLIS R. MARKLEY.
